SWING RAIL SWITCH

Filed Aug. 5, 1929

UNITED STATES PATENT OFFICE

WILBER E. McELDOWNEY, OF DENVER, COLORADO

SWING-RAIL SWITCH

Application filed August 5, 1929. Serial No. 383,437.

My invention relates to swing-rail switches for railway tracks. A principal object is to provide efficient and positive actuating means for a swing-rail switch, the ends of which swing an unequal amount, and to provide means for locking same in either of its two operating positions.

Another object is to provide rotary holding means for the swing-rail, which will firmly hold the rail against lateral displacement, but allow longitudinal movement under stress and during expansion and contraction of the rail.

Still other objects reside in novel details of construction and in novel combinations and arrangements of parts, which will more fully appear in the course of the following detailed description.

In the drawings like reference characters 20 designate similar parts in the several views.

Figure 1 is a plan view of a swing-rail switch embodying the foregoing objects.

Figure 2 is an elevation of the switch looking in the direction of the arrow "A" of Figure 1.

Figure 3 is an enlarged section taken on the line 3—3 of Figure 1.

Figure 4 is an enlarged section taken on the line 4—4 of Figure 1.

Referring more specifically to the drawings, the reference numeral 5 designates the base plate upon which the switch rests.

Rails 6 and 7 leading to the switch are spaced apart and a wedge-shaped filler block 8 is disposed between these rails. The end face of the filler block nearest the switch has sockets 9 for lock bolts on the switch-rail, hereinafter to be described.

Stop members 10 and 12 are respectively fastened to the sides of the rails 6 and 7 by bolts 13 that pass through the rails 6 and 7, the filler block, and the stop members 10 and 12.

Rails 14 and 15 leading to the switch at the opposite end are tapered off on adjacent sides, as is common in switches, and fitted together. A socket 17 is provided between the rails to hold lock bolts on the switch rail, hereinafter to be described.

Stop members 18 and 19 are fastened on opposite sides of the rails 14 and 15. Bolts 16 pass through the stop members 18 and 19 and the rails 14 and 15 to fasten same together.

The numeral 20 designates the swing rail itself. The pivotal point of the rail is indicated at 21. The means for holding the rail in position while it is being swung around this point is as follows:

A seat 22 is usually provided to raise the height of the rail to equal that of the incoming rails where the latter are raised. Lipped gibs 23 have their lips placed over the flanges of the rail to hold the latter against its seat. The side of the gib next to the rail is straight, while the opposite edge is arcuate to fit in a keeper 24 that has a similarly shaped side. A bearing block or keeper 24 is provided for each gib on either side of the rail.

The keepers are fastened to the base plate by bolts 25. Bolts 26 between the bolts 25 also pass through the keepers and provide shafts for rollers 28 rotatably supported on the keepers.

Preferably near the end of the rail 20 having the longest swing, the rail rests in a chair 27. The chair has a passage the shape of the web and flanges of a rail, so that a rail is easily inserted through the passage and thus seated in the chair. The chair has grooves 28 adjacent to and on either side of the rail for the aforementioned lock bolts.

The chair carries rollers 29 at opposite sides of the rail. Vertical stub shafts 30 for the rollers are vertically disposed in the chair, whereby the rollers are made to rotate in a horizontal plane.

Cams 31 and 31a are pivotally mounted on supports 32 on the base plate. The cams are arranged to engage the rollers 28 continuously irrespective of the position of the swing-rail. Connecting bars 33 and 34 are used to connect the cams with operating means hereinafter to be described. These bars contact with the rollers 28, which prevent sidewise movement of the bars and allow same to slide easily. Links 35 connect bosses 44 on the cams 31 and 31a with the bars 33 and 34 respectively.

Brackets 36 and 37 respectively mounted on the bars 33 and 34 carry lock bolts 38 and 39 that move in the recesses 28. The bars extend toward the opposite end of the swing-rail, and near such ends carry brackets 40 and 41. 5 These brackets in turn carry and operate lock bolts 42 and 43.

Any suitable operating means may be provided for the bars 33 and 34. The means 10 shown comprises a yoke 45 extending under the base plate and pivotally mounted on a bolt 46' that extends through the seat 22 and base plate 5, arms 47 connecting the yoke with the bars 33 and 34, rigid arms 48 on the yoke, and rods 49 connecting the arms 48 with any conventional means to throw the switch. 15

In the operation of the present switch, the cams 31 and 31a move the switch rail laterally from one position to the other about the 20 pivotal axis 21. The gibs turn in their keepers to allow the rail to rotate when the switch is "thrown". The gibs, however, allow longitudinal movement of the rail. Thus when 25 wheels of a railway car strike the switch rail, the end of the switch rail is driven against the end of the abutting rail.

Heretofore, it has been suggested to rotate a switch swing rail about a king pin, which prevents longitudinal displacement of the rail. This king pin must, in such a construction, bear the endwise thrust of the swing rail. By the present construction this thrust is absorbed by an abutting rail, as explained. 30

35 In the position shown in Figure 1, the bolt 38 has been pushed home into the recess 9 nearest the stop 12 and the bolt 43, which is at the opposite end and on the opposite side of the swing rail, has been pushed home in the 40 recess 17.

45 When the switch is "thrown," the operating means moves the bars 33 and 34 in opposite directions. The first portion of the movement of these bars withdraws the bolts 38 and 43 from their recesses, without any lateral movement of the swing rail.

50 While any movement of the bars 33 and 34 rotates the cams, the first portion of this movement, while the bolts are being removed, does not move the swing rail. This is due to the fact that the ends of the cam faces describe small arcs with the pivot of the cam as a center.

55 While the rollers 29 are riding on these small arcs of the cams, no motion is transmitted to the rail. However, as rotation of the cams continues, the inclined faces of same engage the rollers. One cam moves the rail laterally while the other makes room for the 60 advancing rail. In this manner, the cams are continuously in contact with the rollers 29 throughout the throwing of the switch.

65 When the rail has reached the position opposite to that shown in Figure 1; i. e., the rail is in contact with the stops 10 and 19, the final

movement of the bars 33 and 34 pushes the bolt 39 into the recess 9 nearest the stop 10 and the bolt 42 into the recess 17. The switch rail is then firmly locked in position. The reverse movement of this operation is believed apparent from the foregoing description. 70

What I claim and desire to secure by Letters Patent is:

1. In a swing-rail switch, a swing rail, 75 means to prevent vertical displacement of the rail during swinging, comprising a member in contact with the rail and a relatively fixed bearing block keeping the member in position, the member and block having adjoining arcuate surfaces for rotary movement of the member in and relative to the block.

2. In a swing-rail switch, a swing rail, gibs at either side of the rail having lips extending over the flange thereof and having an 80 arcuate edge, a bearing block having a complementary arcuate edge engaging said edge of the gib, means holding the block in a fixed position, and mechanism to swing the rail and the accompanying gibs the gib and block being in engagement during such swinging motion. 85

3. In a swing-rail switch, a swing rail, rollers on the rail, cams disposed to bear 90 against the rollers and swing the rail in opposite directions, and means to operate the cams.

4. In a swing-rail switch, a swing rail, cams disposed to swing the rail in opposite 100 directions, and means to operate the cams, including sliding bars and pivoted links connecting the bars with the cams.

5. In a swing-rail switch, a swing rail, rollers on the rail, rotary cams contacting 105 with the rollers and disposed to swing the rail in opposite directions, and means to rotate the cams, including sliding bars having link connections with the cams.

6. In a swing-rail switch, a swing rail, a chair for the rail, rollers on the chair, cam means contacting with the rollers to swing 110 the rail in opposite directions, and means to operate the cams.

7. In a swing-rail switch, a base plate, a 115 chair on the plate, a rail in the chair mounted to swing about a pivotal axis, rollers on the chair, rotary cams pivotally mounted on the plate to engage the rollers continuously during rotation of the cams, and means to rotate 120 the cams.

8. In a swing-rail switch, a swing rail, a lock for the rail, means including a cam to swing the rail, and mechanism to operate the cam at the time of operation of the lock, the 125 face of the cam having non-actuating portions, whereby the rail will not be moved while the lock is being operated.

9. In a swing-rail switch, a swing rail, a lock for the rail, mechanism to operate the 130

lock, and cam means, disposed to swing the rail, operated by said mechanism.

10. In a swing-rail switch, a swing rail, a lock for the rail, mechanism to operate the lock, and rotary cam means disposed to swing the rail, the mechanism having a connection with and thereby operating said cam means.

11. In a swing-rail switch, a swing rail, a lock for the rail, a sliding bar operating said lock, and cam means disposed to swing the rail, operated by the sliding bar.

12. In a swing-rail switch, a swing rail, a rotary support for the rail, sliding means for locking the rail in position, and rollers on the support disposed to guide the sliding means.

13. In a swing rail switch, a swing rail having a contact member, cam means to swing the rail disposed to have a sliding contact with said member, and mechanism to operate the cam means.

14. In a swing rail switch, a swing rail, a lock for the swing rail, cam means for moving the swing rail in opposite directions, and sliding means connected to operate the lock and said means by a single sliding movement.

In testimony whereof I have affixed my signature.

WILBER E. McELDONNEY.
